C. E. & R. G. CHADDOCK & G. A. KURZ.
REVERSIBLE GLOVE.
APPLICATION FILED MAY 11, 1910.

1,136,587.

Patented Apr. 20, 1915.

UNITED STATES PATENT OFFICE.

CHARLES E. CHADDOCK, RICHARD G. CHADDOCK, AND GUSTAVE A. KURZ, OF
ZANESVILLE, OHIO.

REVERSIBLE GLOVE.

1,136,587.

Specification of Letters Patent. Patented Apr. 20, 1915.

Application filed May 11, 1910. Serial No. 560,714.

To all whom it may concern:

Be it known that we, CHARLES E. CHADDOCK, RICHARD G. CHADDOCK, and GUSTAVE A. KURZ, citizens of the United States, residing at Zanesville, in the county of Muskingum and State of Ohio, have invented certain new and useful Improvements in Reversible Gloves, of which the following is a specification.

10 This invention relates to improvements in reversible gloves.

In the manufacture of reversible gloves, particularly those made of fabric, it has been customary to form the opening which 15 receives the thumb member of heart-shape or other such configuration, having sharp corners, and the blank for forming the thumb member was made of such shape as would fit the configuration of the opening.

20 It has been found that this construction tends to weaken the fabric, in that the material, which is of course, mesh, tears at the sharp corners, and in time the glove becomes useless. Furthermore, the foregoing 25 construction involves waste of material.

This invention aims to overcome the objectionable features, in that we provide a substantially round thumb opening in the body portion of the glove, and so shape the 30 blank from which the thumb piece is formed that it will snugly fit the opening. By forming a round thumb opening, liability of ripping the material at any one particular point is entirely removed, as the strain is 35 equally distributed when the thumb piece is stitched. In addition to the shape of the opening, the thumb piece is formed with a deep notch, the walls of which are gradually curved in an arc from the fold line of 40 said piece to, and intersecting the side walls. Hence, when the blank is folded, it is substantially curved and fits snugly the opening in the body portion, thus the strain in any direction is the same.

45 Our invention therefore relates primarily to the construction and arrangement of the thumb piece, and the opening which receives the latter.

For a full understanding of the invention, reference is to be had to the following description and accompanying drawings, in which:

Figure 1 is an elevation of a reversible glove embodying the improvements of our 55 invention; Fig. 2 is a view of the blank out

of which the body portion of the glove is formed; Fig. 3 is a view of the blank out of which the thumb-piece is formed; and, Fig. 4 is a similar view of one of the finger fourchettes.

Corresponding and like parts are referred to in the following description and indicated in all the views of the drawings by the same reference characters.

Our improved glove may be constructed 65 of canvas, duck, leather or any other substance, according to the uses to which the gloves are to be put, and embodies in all only five distinct parts.

The main body portion 1 of the glove is 70 initially formed as a blank with a straight wristband edge 2, substantially straight side edges 3 and a fluted upper edge 4. The blank or body portion 1 is slotted longitudinally from the fluted edge 4, the slits, 75 designated 5, defining half finger portions 6. At the middle of the blank there is no slit, the blank at this point serving to produce a double finger portion 7 which is designed to constitute the index or fore- 80 finger of the glove. In line with the finger portion 7, and close to the wristband edge 2, the body portion is formed with a circular thumb receiving opening 8. In addition to the blank or body portion 1, 85 the glove embodies substantially cigar-shaped fourchettes 9 which taper toward their ends, as shown, the widest portion being at the middle and each fourchette being cut as an integral structure. By the 90 provision of the cigar-shaped fourchettes 9, the side edges of the finger portions 6 are connected together to form the completed fingers, and the side edges of the finger portion 7 are correspondingly connected so 95 that the fingers will have a tendency to lie straight out from the palm portion on the glove and fit as easily in one direction or the other, so that the glove may be used on either hand. It is to be particularly noted

that the thumb portion 10, which is stitched around the thumb opening 8, is also a single piece of material, being in blank form provided in one edge with a V-shaped notch 11 which adapts it to form the thumb when 105 stitched to the body portion of the glove. The walls of the V-shape notch gradually curve in an arc from a medial line to and intersect the side walls, as clearly shown in Fig. 3. The side walls of the thumb piece 110

converge, and at the bottom they are curved toward each other to the center of the blank, the curved portions coming together in alinement with the meeting point of the 5 arch-shaped walls of the V-shaped notch 11. This construction forms a slight notch at the bottom of the blank. The inner side of the thumb piece, in the completed glove, presents an unbroken or unstitched surface, 10 as shown, as does also the adjoining side of that stall or portion of the glove which is adapted to receive the index finger of the hand.

The main body portion 1 is folded along 15 a medial line and stitched, so also the thumb piece is folded on a medial line and stitched. Then the thumb piece is inserted in the round opening 8, and stitched entirely around.

20. A glove constructed in accordance with our invention possesses decided advantages over other gloves known to us, inasmuch as liability of tearing around the thumb piece at any particular point is obviated. When 25 the thumb piece is stitched within the round opening, the pull and the strain when using the glove is spread out and equalized over an increased area which prevents the thumb piece tearing away from the main body 30 portion of the glove.

Having thus described the invention, what is claimed as new is:

1. A reversible glove comprising a body portion folded along a medial line and 35 stitched at the adjacent edges to produce a palm and a back, the forward edge of the body portion being provided with vertical slits forming the second, third and little fingers and a solid intermediate portion of 40 twice the width of said fingers and adapted, when the body portion is folded to form the index finger, there being a single thumb receiving opening formed in the body portion in alinement with the fold of the index finger and spaced inwardly from the rear edge 45 of said body portion, said thumb receiving opening being substantially circular in shape, and a thumb piece adapted to fit in said circular opening and having converg-

ing side walls and vertically alined V- 50 shaped notches formed in the center of its upper and lower ends to permit the thumb to be folded along the longitudinal center thereof to produce mating portions of equal size and shape, the converging walls of the 55 thumb piece being connected by a line of stitching arranged on the upper face of the thumb and in alinement with the fold of the index finger.

2. A reversible glove comprising a body 60 portion folded along a medial line and stitched at the adjacent edges to provide a palm and a back, the forward edges of the palm and back having slits to form fingers, the body portion having a thumb receiving 65 opening located below the top of the body portion with its center in alinement with the medial line of fold of the body portion, said thumb receiving opening being substantially 70 circular in shape, and a folded thumb piece 75 fitting in said opening and comprising a body portion having converging side walls and vertically alined V-shaped notches formed in the center of the upper and lower ends thereof, the upper notch being of 80 greater depth than the lower notch and the inclined walls of the notch in the upper end of the thumb piece being gradually curved in an arc from the fold line of said thumb piece to and intersecting the converging 85 side walls thereof, the curved arc-shaped walls corresponding to the circular opening in the body portion when the thumb piece is folded, said thumb piece having the curved 90 walls of the notch in the upper end thereof stitched to the body portion around the circular opening and having its converging side walls connected by a line of stitching arranged in alinement with the medial fold line of the body portion of the glove. 90

In testimony whereof we affix our signatures in presence of two witnesses.

CHARLES E. CHADDOCK. [L. S.]
RICHARD G. CHADDOCK. [L. S.]
